Design No. 11,253, dated June 17, 1879

UNITED STATES PATENT OFFICE

FELIX MEIER, OF DETROIT, MICHIGAN.

DESIGN FOR CLOCK-CASE.

Specification forming part of Design No. **11,253**, dated June 17, 1879; application filed May 5, 1879.
[Term of patent 14 years.]

To all whom it may concern:

Be it known that I, FELIX MEIER, of the city of Detroit, in the county of Wayne and State of Michigan, have originated a Design for a Clock, of which the following is a full, clear, and exact description, reference being had to the accompanying photographic illustration, making part of this specification.

A represents the base of the frame or case, upon the corners of which are placed the mythological figures B. C represents that part of the case in which the pendulum vibrates, and this is surmounted by the case D, which incloses the operating parts, upon the top of which rests the platform E surmounted by the dome F, upon the top of which is placed a symbolic figure, G. The front face of that part of the case which incloses the operating mechanism is provided with a dial, H, the periphery of which is divided into thirty-one equal and numbered spaces representing a calendar and an index-finger, by means of which the days of the month are in succession designated. This front is also provided with small openings a b, through which, in succession, are presented the names of the months and days of the weeks in regular succession, and is ornamented with the busts c of celebrated inventors. The center dial of the front is divided into quarters, representing the four quarters, d, of the year, and is also provided with a representation of the sun e, and an orrery system, f, representing the planets of the solar system. It is also provided with a representation of the earth, g, and its satellite moon h, the sun, earth, and moon being connected with the internal mechanism by means of which their various revolutions and phases will be at all times accurately shown, while the orrery system is so connected with such mechanism as to indicate the revolution of the planets around the sun. The calendar-dial is surrounded by a system of twelve small clock faces or dials, six of them being arranged on either side of the calendar-dial, with a central and larger clock-dial immediately below the vertical center of the calendar-dial. This latter clock-dial is designed to give accurate time at the place where the clock may be located, while the rest of the clock-dials will indicate, as set, correct time in different parts of

the earth, each of said clock-faces being connected with a train which moves the hands upon all of them. Upon one side of the face is represented, as standing in the niche I, a child, holding in one hand a bell and in the other a hammer. This niche is supported upon the head of an ornamented bust, J, and the figure of the child is so connected with the internal mechanism that the child will strike the bell once at the expiration of the first quarter of the hour, as indicated by the central clock-dial, i.

K represents a niche on the opposite side of the case from the niche I, and is of like form and similarly supported. This niche is provided with a figure of a youth which carries a bell and hammer, and is so connected with the interior mechanism that the figure will strike the bell twice at the termination of the second quarter of the hour. L is a similar niche, supported upon scroll-work, as shown, and incloses the figure of a young man, with hammer and bell, so connected that the bell will be struck three times at the expiration of the third quarter of the hour. M is a niche similar to the niche L, supported in like manner and opposite the same, and which incloses a figure of a man in more advanced years provided with hammer and bell, and so connected that the bell will be struck four times at the closing of the fourth quarter of the hour. N is another niche, placed over the vertical center of the calendar-dial, and incloses a symbolical figure of "Time," and provided with a hammer and bell, so connected that it will strike the hour, as indicated upon the dial i.

Upon the platform E there is a statue, k, of Washington, placed upon a proper pedestal. Doors l are found near each end of this platform, with servants m to open and close the doors, as hereinafter described.

n represents walking figures dressed in the appropriate costume of their generation, and representing in successive order the various presidents of the United States since the days of Washington. These figures of presidents and of the servants are so connected with the interior mechanism of the clock that at the expiration of each successive hour, as indicated by the dial i, the servants open the doors and

the figures of the presidents, in the chronological order of their various administrations, enter upon the platform through one door, pass along the front of the platform, and each figure in turn salutes as it passes the statue of Washington, and they then pass out through the opposite door, and at this time both doors are closed by the attending servants.

What I claim as my invention is—

1. The design of the case **D**, which incloses the mechanism of the clock, provided with the central calendar-dial, **H**, representation of the sun **e**, the orrery system **f**, the representation of the earth **g**, and moon **h**, said calendar being divided, as shown, into four quarters representing the earth's seasons.

2. In combination, the calendar-dial **H**, the central clock-dial, **i**, the series of clock-dials surrounding said calendar-dial, the busts **e**, and the openings **ab**, through which the names of the days and months are presented, as a design for a clock-front.

3. The design of the niches **L M**, supported as shown, each niche inclosing a figure of a man provided with hammer and bell, substantially as shown.

4. The design of the doors **l**, servants **m**, statue **k**, and figures of the presidents **n**, with the platform **E**, supporting the dome **F**, surmounted by the symbolical figure **G**, substantially as shown.

5. The design of a clock-case provided with base **A**, surmounted by mythological figures **B**, supporting the pendulum-vibrating section **C**, the mechanical inclosing-case **D**, with the dials, niches, figures, doors, platform, and dome **F**, substantially as shown.

FELIX MEIER.
